GAME TABLE

Application filed August 4, 1931. Serial No. 555,066.

This invention relates to coin-controlled game tables adapted for playing games of skill with balls and cues.

The game table of my invention comprises an oblong rectangular casing, the upper wall of which is moderately inclined to the horizontal and constitutes a game board. Upon the surface of the board, and spaced from its sides and ends, are a group of longitudinally extending ribs, equally spaced apart and forming a plurality of parallel channels. At the upper end of the board, and spaced from the upper ends of the channels, is a curved shoulder against which balls are projected by a cue from a point near the lower end of the board, and this shoulder directs the balls over the open ends of the channels, from whence they will roll into the channels, and if the player exercises sufficient skill, particular balls may be rolled into particular channels. The channels and the balls are suitably numbered and the score made by the player is computed from these numbers after all of the balls have been played into the channels.

The channels are closed at their lower ends and are covered by a glass plate so that a ball cannot be touched while in a channel, and in order to prevent the balls from being rolled out of the channels, as by tilting the table, check valves are arranged in the several channels, these valves permitting the balls to roll down to the stop board, but preventing their return.

After a game has been played, the balls remain in the lower ends of the channels until they are released by the operation of a coin-controlled device. When this device is operated, after the insertion of a coin, a section of the game board rocks downwardly and the balls drop into a pocket where they are trapped until the handle of said device is returned to its normal position and the tilting section of the game board is returned to its normal position. During these return movements the balls are released from the trap and pass into a chute or runway by which they are returned to the lower end of the game board where they may be picked up and used to play another game. The trap referred to, by rea-

son of its association with the tilting section of the game board and the coin-controlled device, makes it impossible for a player to play more than one game for each coin inserted in the machine.

In the accompanying drawings:

Fig. 1 is a top plan view of the game table;

Fig. 2 is a vertical section through the same on the line 2—2 of Fig. 1;

Fig. 3 is a horizontal section on the line 3—3 of Fig. 4;

Fig. 4 is a transverse section on the line 4—4 of Fig. 3;

Fig. 5 is a detailed view showing some of the parts illustrated in Fig. 2 on a larger scale, and,

Fig. 6 is a bottom plan view of part of the tilting section of the game board with the operating rod connected thereto.

Referring to the drawings, *a* represents the table as a whole, comprising a casing 1 of rectangular form supported on legs 2. Transverse strips 3, secured at their ends to the sides 1^a of the casing, support the bottom 4, and similar strips 5 support the top *b* which constitutes the board on which the game is played. This board is inclined from end to end of the table, and is set below the upper edge of the casing, as shown in Fig. 2, so that the balls will be retained on the board by the walls of the casing.

On the upper surface of the board, and about midway between its ends and sides, is arranged a group of parallel strips *c*, extending longitudinally of the board and spaced apart to form channels *d* for receiving the balls, eleven of these channels being shown in the drawings. The channels are covered by a glass plate 6 so that the balls cannot be taken out of the channels by hand, and the lower ends of the channels are closed by a stop board 6' against which the balls rest when they reach the lower ends of the channels. At a suitable distance upward of the channels from the stop board, a rod 7 extends transversely of the channels beneath the glass plate, and on this rod are loosely hinged a number of check valves *e*, one in each channel, each inclined from the rod downwardly of the channel. When a ball rolls down a

channel it lifts and passes under the check valve, and the latter then drops to its normal position shown in Fig. 2. The ball thus becomes trapped between the stop board and the check valve and cannot be rolled out of the channels, as might otherwise be done by tilting the table.

Flat metal strips 8 are secured to the game board, in line with the stop board 6' and extending from the sides 1^a of the casing to the groups of strips which form the channels. The balls are placed against the upper edge of either one of these strips and shot upwardly against the curved surface 9 which directs them over the open ends of the channels, and if the proper force and "english" are applied, they will drop into the channels. The balls are numbered as in the game of pool and the channels are also numbered, these latter numbers being conveniently placed upon the check valves, as shown in Fig. 1.

A section b' of the game board which underlies the lower ends of the strips or ribs e is connected by a hinge 10 to the under side of the main part of the board and is normally held in position flush with the main part by a counter weight arm 11, which is within the casing. In order to release the balls from the channels, by tilting the section b', it is necessary to insert a coin in a coin-operated device f and then turn a handle 12 thereon through an angle of 90°. The coin-operated device is of standard make and need not be described. This device is arranged upon the lower end portion of the game board, as shown. When the coin has been inserted, it operates as a connector to connect the handle 12 with the shaft 13 which extends into the casing and has a crank arm 14 from which projects a pin 15 which connects the arm with one end of a link 16. The other end of the link is connected to one part 17^a of a hinge 17, the other part of the hinge being fastened to the bottom of the section b' of the game board floor. When the knob or handle of the coin-controlled device is operated to move the link 16, the latter operates, as shown in Fig. 5, to press the part 17^a of the hinge backward against the stop 18, fastened to the section b', and then, by further movement, to tilt the floor section as indicated in dotted lines, thus releasing the balls from the channels. When the handle 12 of the coin-controlled device is returned to normal position, the counter weight arm rocks the section b' to its normal position. A spring (not shown) is provided for returning the handle of the coin-controlled device and the crank arm to normal positions when the operator releases the handle. The coins drop into a box 19 in a compartment 20 which has a key-controlled door 21.

An inclined runway 22 is arranged below the tilting section of the game board, to re-

ceive the balls and conduct them to the end of the table at which the player stands; but the balls are not allowed to pass directly from the tilting section to the runway. Instead, they are trapped in a trough or pocket g which extends transversely of the table beneath the tilting section. This trough has a stationary bottom piece 23 and a piece 24 which is hinged to the opposite end of the trough and connected by a link 25 to the tilting section b'. When the section b' is in normal position, the bottom piece 24 of the trough is raised as shown in full lines in Fig. 4 so that its free end is above the lower end of the bottom piece 23, leaving a space between the meeting ends of these bottom pieces through which the balls may pass to the runway 22; but when the section b' is tilted, the bottom piece 24 is lowered to close the outlet of the trough, as shown in dotted lines in Fig. 4. From this it will be evident that when the coin-controlled device is operated to tilt the section b' to release the balls from the channels, the outlet of the trough g will be closed and the balls will be trapped in said trough. When the coin-controlled device is released and the tilting section b' is returned to normal position, the lifting of the bottom section 24 will release the balls and allow them to pass out into the runway 22.

At the end of a game, the balls will be within the channels, resting against the stop board, as indicated in Fig. 1. In order to play another game, a coin must be inserted in the coin-operated device and the player then turns the handle of said device to rock the tilting section of the game board and permit the balls to roll into the trough g where they are trapped by the lowering of the bottom part 24 simultaneously with the movement of the tilting section. The player must return the handle of the coin-controlled device to normal position, or allow it to be returned by its spring, in order to open the trap and allow the balls to pass into the runway. When this is done, the tilting section of the board is returned to its normal position. The player then takes the balls from the runway and places them on the board against the strips 8, and, with a cue, shoots them into the channels where they become trapped by the check valves. The numbers on the check valves, in association with the numbers on the balls, determine the score when the game is completed. The purpose of trapping the balls between the channels and the runway or return chute is to prevent the possibility of playing more than one game by the insertion of a single coin in the coin-controlled device. If the balls went directly from the channels to the return chute, a player might, by turning the handle of the coin-controlled device through 90°, release the balls from the channels and hold said handle

with one hand to keep the tilting section of the board depressed, and roll the balls with the other hand so that they would pass through the channels and directly into the return chute, from whence they could be removed and rolled over and over again. Of course the balls would not be retained on the game board, but by noting the channels through which they pass and the numbers on the balls, the game might be played in this way. By providing the trap, however, between the tilting section of the game board and the runway and causing the door of the trap to move with the tilting section of the board, it is impossible to play more than one game for each coin inserted in the coin-controlled device. The check valves in the channels prevent the balls from being rolled out of the channels by tilting the table and the glass plate over the channels prevents removal of the balls from the channels by hand.

What I claim is:

1. A game table adapted for playing games with rolled balls comprising an oblong game board having a transversely extending curved shoulder at its upper end against which the balls may be projected, a group of parallel ribs and intervening channels extending longitudinally of the board and spaced from one of its sides and from said shoulder, the lower ends of said channels being closed and the upper ends being open to receive the balls, check valves within the channels adapted to permit the balls to roll downwardly therein and to prevent their return, a transparent covering extending over said channels, and means for releasing the balls from the lower ends of the channels.

2. A game table adapted for playing games with rolled balls comprising an oblong game board having a transversely extending curved shoulder at its upper end against which the balls may be projected, a group of parallel ribs and intervening channels extending longitudinally of the board and spaced from one of its sides and from said shoulder, the lower ends of said channels being closed and the upper ends being open to receive the balls, check valves within the channels adapted to permit the balls to roll downwardly therein and to prevent their return, a transparent covering extending over said channels, said board having a movable part at the lower ends of the channels for releasing the balls, and coin-controlled means for actuating said part to release the balls from the channels.

3. A game table adapted for playing games with rolled balls comprising an oblong game board having a transversely extending curved shoulder at its upper end against which the balls may be projected, a group of parallel ribs and intervening channels extending longitudinally of the board and spaced from one of its sides and from said shoulder, the lower ends of said channels be-

ing closed and the upper ends being open to receive the balls, check valves within the channels adapted to permit the balls to roll downwardly therein and to prevent their return, a transparent covering extending over said channels, said board having a movable part at the lower ends of the channels for releasing the balls, coin-controlled means for actuating said part to release the balls from the channels, means for trapping the balls when they are released from the channels, and means for releasing the balls from the trap when said movable part is returned to its normal position.

4. A game table adapted for playing games with rolled balls comprising an oblong game board having a transversely extending curved shoulder at its upper end against which the balls may be projected, a group of parallel ribs and intervening channels extending longitudinally of the board and spaced from one of its sides and from said shoulder, the lower ends of said channels being closed and the upper ends being open to receive the balls, check valves within the channels adapted to permit the balls to roll downwardly therein and to prevent their return, a transparent covering extending over said channels, said board having a movable part at the lower ends of the channels for releasing the balls, coin-controlled means for actuating said part to release the balls from the channels, means for trapping the balls when they are released from the channels, means for releasing the balls from the trap when said movable part is returned to its normal position, and a return chute below the trap for receiving the balls.

5. A game table adapted for playing games with rolled balls comprising an oblong game board having a transversely extending curved shoulder at its upper end against which the balls may be projected, a group of parallel ribs and intervening channels extending longitudinally of the board and spaced from both of its sides and from said shoulder, the lower ends of said channels being closed and the upper ends being open to receive the balls, numbered check valves within the channels adapted to permit the balls to roll downwardly therein and to prevent their return, a transparent covering extending over said channels, and means for releasing the balls from the lower ends of the channels.

6. A game table adapted for playing games with rolled balls comprising an oblong game board having a transversely extending curved shoulder at its upper end against which the balls may be projected, a group of parallel ribs and intervening channels extending longitudinally of the board and spaced from one of its sides and from said shoulder, the lower ends of said channels being closed and the upper ends being open to receive the balls, check valves within the

channels adapted to permit the balls to roll downwardly therein and to prevent their return, a covering extending over said channels, said board having a part at the lower ends 5 of the channels movable to release the balls, a trap below said part, said trap having a door connected to said part and adapted to close when said part is moved to release the balls and to open when said part is returned 10 to normal position.

7. A game table adapted for playing games with rolled balls comprising an oblong game board having a transversely extending curved shoulder at its upper end against 15 which the balls may be projected, a group of parallel ribs and intervening channels extending longitudinally of the board and spaced from one of its sides and from said shoulder, the lower ends of said channels 20 being closed and the upper ends being open to receive the balls, check valves within the channels adapted to permit the balls to roll downwardly therein and to prevent their return, a covering extending over said channels, said board having a hinged section at 25 the lower ends of the channels for releasing the balls, coin-controlled means for tilting said section to release the balls from the channels, a trap below said section for trapping 30 the balls when they are released from the channels, said trap having a door connected with said section and adapted to close when said section is moved to release the balls and to open when said section is returned 35 to normal position.

In testimony whereof I affix my signature.
LACY B. McCORMICK.
